US00D991945S

(12) **United States Design Patent** (10) Patent No.: **US D991,945 S**
Sprenger et al. (45) Date of Patent: ** Jul. 11, 2023

(54) **PORTION OF A DISPLAY PANEL WITH GRAPHICAL USER INTERFACE**

(71) Applicant: **Endress+Hauser Flowtec AG**, Reinach (CH)

(72) Inventors: **Johannes Sprenger**, Lörrach (DE); **Markus Hoh**, Bonvillars (FR); **Daniel Wagner**, Pfaffenweiler (DE); **Andreas Wiedmer**, Sissach (CH); **Kevin Martin**, Therwil (CH)

(73) Assignee: **Endress+Hauser Flowtec AG**, Reinach (CH)

(**) Term: **15 Years**

(21) Appl. No.: **29/789,130**

(22) Filed: **Sep. 2, 2021**

(57) **CLAIM**

The ornamental design for a portion of a display panel with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The single FIGURE is a front view of a portion of a display panel with graphical user interface.

The broken line showing of portions of the graphical user interface form no part of the claimed design.

**1 Claim, 1 Drawing Sheet
(1 of 1 Drawing Sheet(s) Filed in Color)**
